INTRAVENOUS STAY

Monroe F. Richman, 4444 Libbit,
Encino, Calif. 91316

Filed Oct. 16, 1972, Ser. No. 297,858

Term of patent 14 years

Int. Cl. D24—04, 99

U.S. Cl. D16—1 R

FIG. 1 is a perspective view of the intravenous stay of the invention taken from the front and to one side of the stay, and from above the stay;

FIG. 2 is a top plan view of the stay, the bottom being identical; and

FIG. 3 is a side view of the stay, both sides being identical.

The intravenous stay shown in the drawing clamps around a pole holding a bottle of medication for intravenous feeding and around the neck of the medication for preventing vibration and relative movement between the bottle and the pole.

I claim:

The ornamental design for an intravenous stay, substantially as shown and described.
